HANGER COVER

Ralph S. Reiner, Steubenville, Ohio

Application November 9, 1948, Serial No. 59,155

2 Claims. (Cl. 223—98)

1

This invention relates generally to hanger covers and more particularly to improved hanger cover constructions in which the retention and indication of the garment are provided for.

The most useful and satisfactory method of supporting garments in home storage and while on display in stores has been the placing of the garments on hangers. In order that the hangers shall not snag the clothing to cause raveling and fraying, and in order that the clothing shall not be soiled by the hanger, it is highly desirable that the hanger have a smooth non-absorbent finish. This has been best obtained by varnished or lacquered wood hangers or by hangers which have been moulded of synthetic resins. While it is advantageous that the finish of the hanger be smooth, for the reason given above and so that it will not carry soil from one garment to another, this smoothness offers insufficient friction so that when disturbed, the garment, particularly women's garments, slides off the hanger and falls to the floor. This results in the garment getting dirty and wrinkled. This sliding off of the garment occurs even more frequently when the arms of the hanger have a desirable shoulder angle slope, and when the garments are handled by prospective customers on the racks and display racks in stores or similar establishments.

Garments while hanging and supported upon hangers tend to collect dust and soil and it has heretofore been proposed to put a cover over the upper part of the garment on the hanger to protect it from such dust and soil. This protection has been effective providing that the garment itself did not fall off the hanger. When this did occur however, it was even more bothersome to remove the cover, then replace the garment, and then to put the cover back on again.

It is therefore among the objects of the present invention to provide a novel and useful combination hanger cover having means to retain the garment upon the hanger as well as means to indicate characteristics of the garment or other data relative thereto.

Another object herein lies in the provision of structure of the class described which is capable of quick and easy manipulation.

Another object lies in the provision of a device of the present character which is of simple and foolproof construction so that the article may have a long useful life and so that it may be manufactured at low cost, to have a consequent large distribution and sale.

These objects and other incidental ends and advantages will more fully appear in the progress

of this disclosure and be pointed out in the appended claims.

In the drawings in which similar reference characters designate corresponding parts throughout the several views of each embodiment:

Figure 1 is a view in perspective of a first embodiment of the invention.

Figure 2 is a fragmentary perspective exploded view of parts of Figure 1.

Figure 3 is an enlarged fragmentary sectional view as seen from the plane 3—3 on Figure 1.

Figure 4 is a front elevational view of a second embodiment of the invention. This is a fragmentary view with cover element removed.

Figure 5 is an enlarged fragmentary vertical sectional view as seen from the plane 5—5 on Figure 4.

Turning now to the first embodiment of the invention as shown on Figures 1 to 3 inclusive, the hanger cover, generally indicated by reference character 10 comprises broadly a cover element 12, a plurality of retainer elements 14 and 16, a plurality of indicia holding elements 18 and 20, and a plurality of securing members 22, 23, and 24. The indicia is indicated by reference characters 26 and 28.

The cover element 12 is composed of any suitable flexible dust retarding planar material. I prefer to fabricate the cover element 12 of sheet synthetic resin, such as for example, vinyl copolymer resins. Other similar materials, such as oilsilk, coated textiles, or the like may be used. The cover element 12 includes a front wall 30, a rear wall 32, and a top wall 34. The front and rear walls may be joined to the top wall in any suitable manner as by the bound seams 36 and 38 and the lower free edge of the cover element may be reinforced by the binding 40. The top wall 34 is provided with an opening 42 through which the upper or hook portion 44 of a well known clothes hanger 46 may be upwardly projected. Obviously the lower free edge (covered by the binding 40) may be as low as desired, depending upon the amount of the garment 50 which it is desired to protect. This results in the top wall falling into vertical or side wall portions 48 and 52. While I have shown the cover element 12 as having a top wall of substantial front to rear dimension, where desired this wall may be reduced to infinity and the retainer elements and indicia holding elements held by the securing members at the juncture of the uppermost edges of the front and rear walls 30 and 32. In this event the opening may be formed by an

incomplete joining thereat of the upper edges of the front and rear walls.

The retainer elements 14 and 16 are preferably composed of a resilient material have a predetermined coefficient of friction. Since they are substantially identical in construction, a detailed description of one will suffice for both, the parts on the element 16 being given the next following reference character. Thus the retainer element 14 (see Figure 4) may include a front gripping member 54, a rear gripping member 56, and a top member 58. The top member 58 is provided with a plurality of holes 60 through which pass the securing members 22 and 23, and the top wall 34 has corresponding holes for this purpose, although said last mentioned holes may be produced by the piercing action of the securing members 22 and 23 during assembly. The retainer element 14 is substantially inverted U-shape in cross-section, the front and rear gripping members, in an unstressed condition, being slightly bent toward each other. The distance between the front and rear gripping members is preferably substantially equal to the horizontal thickness of the hanger body 46 thereat so that when the device is in use the front and rear gripping members 54 and 56 may frictionally engage the garment 50 upon the hanger 46. The retainer elements 14 and 16 may be composed for example of spring metal or plastic (synthetic resin). Satisfactory metals include brass, phosphor bronze, stainless steel, and the like. The plastics may include methyl-methacrylate, polyethylene, polystyrene, and the like, in which the plasticizer content is adjusted to provide the desired stability and resiliency. It is desirable that the inner opposed and therefore active surfaces of the gripping members have a slightly roughened or matte surface. This increases the frictional effect thereof, particularly where the fabric of which the garment 50 is composed is slippery. These surfaces should not be excessively rough because they would then mar or roughen the fabric surface.

The indicia holding elements are preferably composed of the same material of which the retainer elements are fabricated, with the added consideration that at least the upper portion shall be transparent. A detailed description of the element 18 will suffice for the both, that is 18 and 20, the corresponding parts on the element 20 being given the next following reference character. Thus the indicia holding element 18 (Figure 4) may include a base, a front transparent panel 68, an upper bend portion 70, and a rear transparent panel 72. The base 62 is provided with holes (not shown) which correspond to the holes 60, and serves to support the front and rear transparent panels in an upright position as well as to anchor and reinforce the attachment of the retainer element 14 to the top wall 34. The bend portion 70 enables the front and rear transparent panels to have relative resilient movement, so that when the indicia 26 on an indicia carrying element 74 is inserted therebetween, said element 74 will be frictionally retained therein, by the compression between the front and rear transparent panels. This feature enables the indicia carrying element to be easily changed so that the information conveyed thereby may be correct at all times, said information being for example, the size, and/or style of the garment, the price, and the name of the store.

In the manufacture of the present device, the

retainer element 14 and the indicia holding element 18 may be held upon the lower and upper surfaces respectively of the top wall 34 by the securing members 22 and 23, which are preferably in the form of rivets, as shown. Depending upon the particular materials of which the cover element, retainer element, and indicia holding element are composed, other equivalent securing means may be used, as for example, staples, screws and nuts, bendable tabs on one of the retainer or indicia holding elements, welding or soldering. The way the parts are assembled is clearly shown in Figure 3 of the accompanying drawings.

The use of the cover 10 is also facilitated by the fact that the front and rear transparent panels 68 and 72 may be manually grasped to aid in the placing of the retainer element 14 upon the shoulder portion of the garment 50 as it is resting upon and supported by the hanger body 46, and also in disengaging the same.

It may thus be seen that I have provided a novel and useful hanger cover construction, which not only protects the clothing from dust and dirt, but also prevents the garment from accidentally slipping off the hanger to fall upon the ground or floor. Convenient handles are provided by the indicia holding elements 18 and 20 which also enable ready identification of the characteristics of the garment as well as other pertinent information. While I have shown, on the hanger cover 10, two assemblies, one adapted to engage one of the garment shoulder portions and the other to engage the other garment shoulder portion, depending upon the type of garment a different number of these assemblies may be used.

Turning now to the second embodiment of the invention illustrated in Figures 4 and 5, for the purpose of avoiding needless repetition, certain of the parts corresponding generally to those of the first embodiment are given the same reference characters with the addition of the prefix "1."

The second embodiment differs from the prior described one principally in that the retainer elements 14 and 16 instead of being carried by the cover element 112 per se, are carried on arm elements 176 and 178, which are in turn supported by the lower part of the hook portion 144 of the hanger 146. The retainer elements 114 and 116 have their top members 158 and 159 elongated and at their inner ends, said top members are secured to the outer ends of the arm elements 176 and 178.

I wish it to be understood that I do not desire to be limited to the exact details of construction shown and described for obvious modifications will occur to persons skilled in the art.

I claim:

1. Hanger cover construction for use in conjunction with a clothes hanger comprising: a cover element and a retainer element; said cover element including front and rear walls joined together by a top wall, and adapted to overlie a garment having shoulder portions in place upon said clothes hanger; said retainer element including a top member and front and rear gripping members disposed substantially at right angles with respect to said top member; said top member of said retainer element having a width substantially equal to that of said hanger, so that said front and rear gripping members may resiliently engage a shoulder portion of a garment supported upon said hanger

to retain said portion upon said hanger; said retainer element being secured to the inner surface of the top wall of said cover element, whereby the engagement of said retainer element with a shoulder portion of a garment supported by said hanger may maintain said cover element in position upon the upper portion of said garment and said hanger.

2. A device as claimed in claim 1 in which the retainer element is provided with indicia carrying means engaging the outer surface of the top wall of the cover element.
